Primary Examiner — Ian Simmons*Assistant Examiner* — Janice Lim(74) *Attorney, Agent, or Firm* — Fabian VanCott; Steven L. Nichols(57) **CLAIM**

The ornamental design for a container for a solid state detergent, as shown and described.

DESCRIPTION

FIG. 1 is an isometric view of a container for a solid state detergent, showing our new design.

FIG. 2 is a front view thereof.

FIG. 3 is a rear view thereof.

FIG. 4 is a side view thereof.

FIG. 5 is an opposite side view thereof; and,

FIG. 6 is a top view thereof.

The broken line portions show unclaimed subject matter only and form no part of the claimed design.

1 Claim, 6 Drawing Sheets(56)
